US00D370146S

United States Patent [19]
Petronio

[11] **Patent Number:** **Des. 370,146**
[45] **Date of Patent:** ****May 28, 1996**

[54] **TOOTHBRUSH HOLDER**

[75] Inventor: **James Petronio**, New York, N.Y.
[73] Assignee: **Colgate-Palmolive Company**, New York, N.Y.
[**] Term: **14 Years**
[21] Appl. No.: **34,051**
[22] Filed: **Feb. 1, 1995**
[52] U.S. Cl. **D6/534**
[58] Field of Search D6/528, 534; D7/551, D7/571, 578; D11/131, 149, 157-158; D19/75, 97; D21/51; D26/9, 16-17; D27/102, 106, 113; 206/362.2, 362.3; 211/60.1, 71; 220/571, 736; 248/110-111
